Primary Examiner — Austin Murphy(74) *Attorney, Agent, or Firm* — Dickinson Wright PLLC(57) **CLAIM**

The ornamental design for a dish drainer, as shown and described.

DESCRIPTION

FIG. 1 is a perspective view of the top of the dish drainer;

FIG. 2 is a top view of the dish drainer;

FIG. 3 is a front view of the dish drainer;

FIG. 4 is a rear view of the dish drainer;

FIG. 5 is a bottom view of the dish drainer;

FIG. 6 is a left side view of the dish drainer;

FIG. 7 is a right side view of the dish drainer;

FIG. 8 is a perspective view of the bottom of the dish drainer; and,

FIG. 9 is a perspective view of the dish drainer with a plurality of dish drainers shown in broken lines stacked on top of one another.

The broken lines showing that dish drainers can be stacked on top of one another as illustrated in FIG. 9 are for illustrative purposes only and form no part of the claimed design.
